PUMP

Victor G. Klein, St. Louis, and Jonathan Kludt, Ladue, Mo., assignors to Lincoln Engineering Company, St. Louis, Mo., a corporation of Missouri

Application November 4, 1940, Serial No. 364,194

22 Claims. (Cl. 221—47.1)

This invention relates to pumps, and with regard to certain more specific features to pumps particularly adapted for pressure delivery of semi-plastic materials.

Among the several objects of the invention may be noted the provision of a pump for pumping semi-plastic materials directly from commercial containers; the provision of a pump of the class described which avoids the necessity for using a long suction tube which would set up too much friction in the case of semi-plastic materials; the provision of a pump of the class described which will provide semi-plastic material under such pressure as will force this material through lines of substantial length; and the provision of a device of the class described which will avoid entrainment of air and hence which will provide air-free delivery. Other objects will be in part obvious and in part pointed out hereinafter. —

The invention accordingly comprises the elements and combinations of elements, features of construction, and arrangements of parts which will be exemplified in the structures hereinafter described, and the scope of the application of which will be indicated in the following claims.

In accompanying drawings, in which is illustrated one of various possible embodiments of the invention,

Fig. 1 is a side elevation showing follower and pump parts in elevated position above a container which is illustrated in section;

Fig. 2 is a view similar to Fig. 1 showing the follower and pump parts depressed into the container;

Fig. 3 is an enlarged vertical section of certain pump parts at the beginning of a suction stroke;

Fig. 4 is a fragmentary view similar to Fig. 3, showing the position of parts at the end of the suction stroke;

Fig. 5 is an enlarged vertical section of a lift cylinder; and,

Fig. 6 is an enlarged horizontal section taken on line 6—6 of Fig. 5.

Similar reference characters indicate corresponding parts throughout the several views of the drawings.

Referring now more particularly to Fig. 1, there is shown at numeral 1 a commercial container for semi-plastics, such as caulking compounds, putty, or the like. It is desired to empty this container by applying a pump directly thereto.

Numerals 3 and 5 show supporting plates between which are spacing and supporting pillars 7. These form a supporting frame in which are tension holders 101 for the container 1.

On the upper plate 5 is carried a manifold 9 for a lift cylinder 11. In the cylinder 11 is a piston 13 on the upper end of a piston rod 15, which passes down through a packing gland 17 on the manifold 9. At the upper end of the cylinder 11 is a buffer spring 19 with which the piston 13 contacts at the upper end of its stroke. This absorbs shock.

In the manifold 9 is an inlet 21 communicating with the lower end of the cylinder 11 and also an inlet 23 which, through a pipe 25, communicates with the upper end of the cylinder 11. Each of the inlets 21 and 23 carries an inlet fitting 29 and 31, respectively, which provides for selective quick-detachable connections with a coupling 33 on the end of a flexible air hose 35. The hose 35 receives air from a supply line 37. By attaching the couplers 33 to one or the other of the fittings 29 or 31, compressed air may be brought under the piston 13 or above it. When the coupler 33 is on one of the fittings 29 or 31, the other fitting serves as an air-relief port for the other side of the piston 13, since there are no check valves in the fittings 29 or 31. The line 37 also supplies a flexible hose 45 for supplying the motive fluid to an engine 41.

The piston rod 15 extends downward where it is attached to a frame 39. This frame supports the fluid engine 41 (air engine in the present example), and its integral valve control 43. The details of the engine and its valve gear are not shown, since these are known (see for example United States Patent 2,215,852 dated September 24, 1940, of Victor G. Klein, and the improvement application thereon of Frank S. Barks and Victor G. Klein, Serial No. 359,034, filed September 30, 1940, for Valve mechanism). The essential features of the engine, so far as the present disclosure is concerned is that it receives an operating fluid over the flexible line 45 which results in reciprocation of a downwardly directed piston rod 47 extending from the engine, provided that resistance to the movement of the rod 47 is not so great as to stall the engine. When said resistance becomes great enough, the engine stops. Pump parts are attached to a plate 49 carried upon spacing pillars 51 extending from the engine 41.

What may be referred to as a pump cylinder is shown at 53, fastened by means of a nut 55 to the plate 49. This cylinder 53 at its lower end is attached to a flared bell 57, flanged at the bottom, as shown at 59, and attached by means of studs and removable wing nuts 61 to a follower plate 63. The plate 63 has a movable fit in the

drum 1. The clearance between the circular edge of the plate 63 and the inner circular wall of the drum 1 need not be snug, but it should be a fairly accurate loose fit. The central portion of the follower 63 has a relatively large opening 65, to communicate with the hollow interior of the bell 57.

The cylinder 53 has an upper bore 67, in which is a closely fitting plunger 69. Below the bore 67 is a counterbore 71, into the lower end of which is screwed a lift cylinder 73. The upper end of the cylinder 73 is formed with a spherical seat 75, for supporting a movable valve seat 77. The lower side of the valve seat is also spherical, and rocks on the supporting seat 75. Double-shouldered means 79 at the lower end of the cylinder 53 serves to axially center the valve seat, but permits rocking movement about any horizontal axis.

The upper side of the valve seat 77 is machined (preferably flat) for sealing engagement with the lower edge of a valve 81. The valve is slidable around an extension 83 from the plunger 69. The upper end of the valve 81 is crenelated as shown at 85, so that fluid may flow around it and into the bore 67 upon a retractive stroke of the plunger 69, or at least to allow a communication between any vacuum in cylinder 67 with counterbore 71.

The counterbore 71 is provided with an outlet 87 with which communicates an outwardly opening double check-valve member 89. The double check-valve member 89 communicates with an accumulator cylinder 91, the opposite end of which is connected at 93 with a flexible line 95 leading to a hand control valve 97. Attached to the valve 97 may be any suitable nozzle for applying the semi-plastic.

At the lower end of the extension 83 (Figs. 3 and 4) is attached an elevator disc 99 which has a good enough fit with respect to the interior of the lift cylinder 73 (Fig. 4) to effect lifting of plastic past valve 81, but said fit is poor enough so that above a certain pressure extrusion will occur of material back through the clearance between the elevator disc 99 and the cylinder 73. This will return to the supply.

Operation is as follows:

The coupling 33 is first attached to the fitting 29, whereupon air pushes up the piston 13 with rod 15 to lift the assembly of pump parts, including the follower 63, as shown in Fig. 1. This permits of placing the container 1 in position on the base 3 after its cover has been removed. The container may be held down in proper axial position by means of tension rods, one of which is shown at 101.

Next, the coupler 33 is removed from the fitting 29, whereupon gravity will carry down the pump parts by their own weight. This applies the follower 63 to the top of the plastic in the container 1. If the plastic is particularly thick and additional force on it is desired, this may be obtained by applying the coupler 33 to the fitting 31. This introduces air pressure above the piston 13 and applies force to the pump assembly via the rod 15. Hence additional force is applied to the follower 63.

When the valve 97 is opened, resistance is released in the outlet 87 and the pump 41 (which was theretofore stalled) automatically starts operation to reciprocate the plunger 69. Starting with the position of the plunger parts shown in Fig. 3, and progressing up to the position shown in Fig. 4, it will be seen that a vacuum will be drawn by the plunger 69 in the bore 67, tending

to unseat the valve 81 and to draw up plastic materials. Such a vacuum alone, it has been found, is not sufficient to pump plastics at desired rates, especially not through long suction pipes. It is for this reason that the bell 57 and extension 83 are used with the elevator disc 99 and lift cylinder 73. The disc 99 serves to push up or elevate the plastic mass which is above it and raise this mass through the lift cylinder 73. After the elevator disc 99 enters the lift cylinder 73, the volumetric displacement of it in this cylinder 73 is greater than that in the bore 67. This is because of the relatively large bore of cylinder 73 and diameter of disc 99. Hence plastic crowds past the valve 81 and this infills the vacuum in 67.

Any further excess that cannot be pushed on is squeezed back and out around the disc 99, and passes back to the supply in the bell 57. Upon a downstroke the valve 81 closes and the compressive action of the plunger 69 compresses material through the outlet 87.

During the upstroke both a vacuum (at 67) and a lifting action (by 99) are used, the lifting action serving not only to infill the vacuum under plunger 69 but also to squeeze plastic toward the outlet 87. The infilling into the vacuum under 69 prepares the plunger 69 for pressing out plastic to outlet 87 upon the downstroke. During the final portions of the downstroke, the elevator disc 99 is quite clear of the lift cylinder 73, so that during all this time (which is substantial) the plastic may in-flow above the disc 99 to form a more or less clinging mass which is ready to be lifted into the lift cylinder 73 upon upward approach of the disc 99 to the cylinder 73.

The purpose of the accumulator 91 is to smooth out pulsations of flow, so that the flow in the line 95 is relatively smooth.

As pumping continues and material is withdrawn from the drum 1, the follower descends, and in view of the weight thereon, and, if desired, additional air pressure from above the piston 13, tends to squeeze material up into the bell 57 and above the elevator disc 99 when lowered as in Fig. 3.

Finally, the condition shown in Fig. 2 is reached, wherein most or all of the material has been withdrawn from the container 1. The coupling 33 may be at this time applied to the fitting 29 and the assembly lifted to the Fig. 1 position, the frame 5, 7 and rods 101 forming positive reaction means between the piston 13 and container 1 while the follower 63 is forcibly separated from the material 10. If the suction action of the follower 63 resists lifting too much, the wing nut 61 may be loosened so that the assembly (down to and including the bell 57) may be withdrawn, after which the disc 63 may be pulled out, the vacuum having been broken by reason of entry of air through the opening 65. The disc may then be reapplied to the bell 57 for application to the next container. The large opening 65 available to atmosphere makes it easy to pick out the follower, if necessary.

The device is applicable to materials, the viscosities of which are such as not to pass between a fairly loose fit between the edge of follower 63 and inner wall of the container 1, while the follower bears a weight or force from above, which is adapted to force the material through the relatively large opening 65 and into the bell 57.

In view of the above, it will be seen that the

several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

We claim:

1. In a pump, a follower for application to the surface of material in a cylindric container, the shape of the follower loosely approximating a cross section of said cylinder with clearance, said follower having an opening for withdrawal of material, a pump located on the follower and withdrawing material through said opening, an engine associated with the pump, means for applying fluid pressure to the engine and pump in the direction of their combined weights, the said fluid pressure and weight of the pump and engine being applied with the follower weight to the material as it is withdrawn from beneath it by the pump, the area of said clearance and of said opening being so related that said force and weight press material through said opening without pressing it through said clearance.

2. In a pump, a follower for application to the surface of material in a container, said follower having an opening for withdrawal of material, a pump cylinder located on the follower for withdrawing material through said opening and having an outlet for delivery of material, an engine associated with the pump cylinder, a plunger reciprocated by the engine and operating in said cylinder, means for applying fluid pressure to the pump and engine in the direction of their weights, the fluid pressure and weights of the pump and engine being applied with the follower weight to the material as it is withdrawn from beneath by the pump, and quick-detachable means between the pump and the follower.

3. In a pump, a frame work, a follower for application to the surface of material in a container, said follower contacting the material on its bottom side and having an opening for withdrawal of material and also being exposed to atmospheric pressure on its top side, a pump cylinder attached to the follower and having an outlet for delivery of material, an engine associated with the pump cylinder, a plunger reciprocated by the engine and operating in said cylinder, fluid-pressure-operated means connected to the frame work for lifting the assembly of follower, engine and pump clear of the container and means attached to the frame work for holding the container in the frame when lifting is effective whereby the follower may be forcibly separated from said material without relieving the atmospheric pressure thereon prior to separation, said framework forming positive reaction means between the fluid-pressure-operated means and the container.

4. In a pump, a follower for application to the surface of material in a container, said follower having an opening for withdrawal of material, a pump cylinder located on the follower and having an outlet for delivery of material, an engine associated with the pump cylinder, a plunger reciprocated by the engine and operating in said cylinder, the weight of the pump and engine being applied to the follower as material is withdrawn from beneath it by the pump, and fluid-pressure-operated means for lifting the assembly of engine and pump clear of the container, said pressure-operated means being also

adapted to apply force to move said assembly and follower against the material, which is in addition to the force of gravity of said engine and pump on the follower.

5. In apparatus of the class described, a frame for receiving an open container for material to be pumped, a cylinder at the top of the apparatus, a piston in the cylinder, a piston rod reaching from said piston downwardly, an engine and pump assembly fastened to said piston rod, a follower supported in connection with said assembly and adapted to move into said container against the surface of material therein, said pump having an outlet and also an inlet through said follower, reciprocation of the pump by the engine resulting in withdrawal of fluid from beneath the follower for delivery to said outlet, means for delivering air beneath said piston to lift the assembly with the follower clear of the container, and means for releasing said air and delivering air above the piston to force said assembly to push the follower against the material in the container to effect an extrusion thereof through said inlet toward the pump.

6. Pump means comprising a follower for engaging the surface of the material to be pumped from a container, said follower having an opening forming a pump inlet, a lift cylinder above the inlet, a pump cylinder communicating with the lift cylinder, a plunger in the pump cylinder, an extension from said plunger passing through the lift cylinder, an elevator disc on the extension movable from a position substantially clear of the lift cylinder to positions within the lift cylinder.

7. Pump means comprising a follower for engaging the surface of the material to be pumped, said follower having a relatively large opening, a relatively large bell-shaped inlet covering the opening, a smaller lift cylinder, a pump cylinder communicating with the lift cylinder, a valve controlling flow from the lift to the pump cylinder, a plunger in the pump cylinder, an extension from said plunger passing through the lift cylinder, an elevator disc on the extension movable from a position substantially clear of the lift cylinder and in the bell-shaped inlet to positions within the lift cylinder, said pump cylinder having an outlet above said valve.

8. Pump means comprising a follower for engaging the surface of the material to be pumped, said follower having an opening, a bell-shaped inlet covering the opening and a lift cylinder, a pump cylinder communicating with the lift cylinder, a plunger in the pump cylinder, an extension from said plunger passing through the lift cylinder, an elevator disc on the extension movable from a position substantially clear of the lift cylinder to positions within the lift cylinder, the clearance between the elevator disc and the lift cylinder being enough for permitting back-flow past the disc, a valve between the disc and the plunger, said pump cylinder having an outlet above said valve.

9. Pump means comprising a follower for engaging the surface of the material to be pumped, said follower having an opening, a bell covering the opening and a lift cylinder thereabove, a pump cylinder communicating with the lift cylinder, a plunger in the pump cylinder, an extension from said plunger passing through the lift cylinder, an elevator disc on the extension movable from a position substantially clear of the lift cylinder and in the bell to positions within the lift cylinder, the clearance between the eleva-

tor disc and the lift cylinder being enough for back-flow when necessary past the disc, a valve between the disc and the plunger, said cylinder having an outlet above said valve, and means for continually forcibly biasing the follower toward the material to extrude it through the opening and into said bell and above the elevator disc.

10. Pump means comprising a follower for engaging the surface of the material to be pumped, said follower having an opening, a lift cylinder, a pump cylinder communicating with the lift cylinder, a plunger in the pump cylinder, an extension from said plunger passing through the lift cylinder, an elevator disc on the extension movable from a position substantially clear of the lift cylinder to positions within the lift cylinder, a valve between the disc and the plunger, said cylinder having an outlet above said valve, and means for continually forcibly biasing the follower toward the material to extrude it through the opening and into said bell and above the elevator disc.

11. Pump means comprising a follower for engaging the surface of the material to be pumped, said follower having an opening, a bell covering the opening and including a lift cylinder thereabove, a pump cylinder communicating with the lift cylinder, a plunger in the pump cylinder, an extension from said plunger passing through the lift cylinder, an elevator disc on the extension movable from a position in the bell to positions within the lift cylinder, the clearance between the elevator disc and the lift cylinder being enough for backflow past the disc, a valve between the disc and the plunger, said cylinder having an outlet above said valve, the volumetric displacement of the elevator disc in the lift cylinder being greater than that of the plunger in the pump cylinder during the part of the stroke in which the disc is in said lift cylinder.

12. Pumping apparatus comprising a pump cylinder, a plunger reciprocating therein, a lift cylinder forming an inlet for said pump cylinder, a bell extending from said lift cylinder, an extension from said plunger passing through said lift cylinder to the bell, an elevator disc on said extension and loosely fitting the lift cylinder, the lift cylinder being in free communication with the bell, a valve between the lift cylinder and the pump cylinder permitting flow only from the former to the latter, said pump cylinder having an outlet located above said valve.

13. Pumping apparatus comprising a pump cylinder, a plunger reciprocating therein, a lift cylinder forming an inlet for said pump cylinder, an extension from said plunger passing through said lift cylinder, an elevator disc on said extension and loosely fitting the lift cylinder and movable from points outside to points inside of the lift cylinder, a valve between the lift cylinder and the pump cylinder permitting flow only from the former to the latter, said pump cylinder having an outlet located above said valve.

14. Pumping apparatus comprising a pump cylinder, a plunger reciprocating therein, a lift cylinder forming an inlet for said pump cylinder, an extension from said plunger passing through said lift cylinder, an elevator disc on said extension and loosely fitting the lift cylinder, a valve between the lift cylinder and the pump cylinder permitting flow only from the former to the latter, said pump cylinder having in communication therewith an outlet located above said valve, the bore of the lift cylinder being larger than

that of the pump cylinder and said elevator disc fitting it loosely enough so that upon an upstroke excess material may be passed back to the bell-shaped portion around said elevator disc.

15. Pumping apparatus comprising a pump cylinder, a plunger reciprocating therein, a lift cylinder therein forming an inlet for said pump cylinder, a bell extending from said lift cylinder, an extension from said plunger passing through said lift cylinder and into the bell, an elevator disc on said extension and loosely fitting the lift cylinder, the lift cylinder being in free communication with the bell-shaped member when clear of the disc, a valve between the lift cylinder and the pump cylinder permitting flow only from the former to the latter, said pump cylinder having in communication therewith an outlet located above said valve, the bore of the lift cylinder being larger than that of the pump cylinder and said elevator disc fitting it loosely enough so that upon an upstroke excess material may be passed back to the bell-shaped portion around said elevator disc.

16. Pumping apparatus comprising a frame for receiving a container for materials to be pumped, a cylinder at the upper end of the frame, a piston in the cylinder, means for introducing air either below or above said piston to lift or to depress it respectively, a piston rod extending down from said piston, an engine and pump assembly supported by said piston rod and movable up and down, a follower carried by said assembly and engageable with the surface of the material in the container and having an opening for passage of said material to the pump, said pump comprising a cylinder, a plunger therein reciprocated by the engine, a bell connecting the cylinder with the opening in said follower, a lift cylinder between the pump cylinder and the bell, an extension from the plunger passing through said lift cylinder and into the bell, an elevator disc on said extension and movable throughout a substantial portion of an upstroke freely in the bell and beyond the lift cylinder and thereafter in the lift cylinder.

17. Pumping apparatus comprising a frame for receiving a container for materials to be pumped, a cylinder at the upper end of the frame, a piston in the cylinder, means for introducing air either below or above said piston to lift or to depress it respectively, a piston rod extending down from said piston, an engine and pump assembly supported by said piston rod and movable up and down, a follower carried by said assembly and engageable with the surface of the material in the container and having an opening for passage of said material to the pump, said pump comprising a cylinder, a plunger therein reciprocated by the engine, a bell connecting the cylinder with the opening in said follower, a lift cylinder between the pump cylinder and the bell, an extension from the plunger passing through said lift cylinder and into the bell, an elevator disc on said extension and movable throughout a substantial portion of an upstroke freely in the bell and beyond the lift cylinder and thereafter in the lift cylinder, said disc having a relatively loose fit in the lift cylinder.

18. Pumping apparatus comprising a frame for receiving a container for materials to be pumped, a cylinder at the upper end of the frame, a piston in the cylinder, means for introducing air either below or above said piston to lift or to depress it respectively, a piston rod extending down from said piston, an engine and pump assembly sup-

ported by said piston rod and movable up and down, a follower carried by said assembly and engageable with the surface of the material in the container and having an opening for passage of said material, said pump comprising a cylinder, a plunger therein reciprocated by the engine, a bell connecting the cylinder with the opening in said follower, a lift cylinder between the pump cylinder and the bell, an extension from the plunger passing through said lift cylinder and into the bell, an elevator disc on said extension and movable throughout a substantial portion of the stroke freely in the bell and beyond the lift cylinder, said disc having a relatively loose fit and being movable in the lift cylinder throughout the remainder of the stroke, said pump cylinder having an outlet above the lift cylinder, a check valve in the outlet and a valve permitting only flow from the lift cylinder toward said pump cylinder, said plunger thereafter forcing the material through said outlet.

19. Pumping apparatus comprising a frame for receiving a container for materials to be pumped, a cylinder at the upper end of the frame, a piston in the cylinder, means for introducing air either below or above said piston to lift or to depress it respectively, a piston rod extending from said piston, an engine and pump assembly supported by said piston rod and movable up and down, a follower carried by said assembly and engageable with the surface of the material in the container and having an opening for passage of said material, said pump comprising a cylinder, a plunger therein reciprocated by the engine, a bell connecting the cylinder with the opening in said follower, a lift cylinder between the pump cylinder and the bell, an extension from the plunger passing through said lift cylinder and into the bell, an elevator disc on said extension and movable throughout a substantial portion of the stroke freely in the bell and beyond the lift cylinder, said disc moving in the lift cylinder throughout the remainder of the stroke and having a loose fit therein, said pump cylinder having an outlet above the lift cylinder, and a check valve permitting only flow from the lift cylinder toward said outlet, the volumetric displacement of the disc in the lift cylinder being greater than the pump plunger during the time that said disc is movable in said lift cylinder.

20. Pumping apparatus comprising a frame for receiving a container for materials to be pumped, a cylinder at the upper end of the frame, a piston in the cylinder, means for introducing air either below or above said piston to lift or to depress it respectively, a piston rod extending from said piston, an engine and pump assembly supported by said piston rod and movable up and down, a follower carried by said assembly and engageable with the surface of the material in the container and having an opening for passage of said material, said pump comprising a cylinder, a plunger therein reciprocated by the engine, a bell connecting the cylinder with the opening in said follower, a lift cylinder between the pump cylinder

and the bell, an extension from the plunger passing through said lift cylinder and into the bell, an elevator disc on said extension and movable throughout a substantial portion of the stroke freely in the bell and beyond the lift cylinder, said disc having a relatively loose fit and being movable in the lift cylinder throughout the remainder of the stroke, said pump cylinder having an outlet above the lift cylinder, and a check valve permitting only flow from the lift cylinder toward said outlet, the volumetric displacement of the disc in the lift cylinder being greater than the pump plunger during the time that said disc is movable in said lift cylinder, said follower being biased against the material by the weight of the pump and engine thereon, and additionally by the action of air upon the upper side of said piston.

21. Pumping apparatus comprising a frame for receiving a container for materials to be pumped, a cylinder at the upper end of the frame, a piston in the cylinder, means for introducing air either below or above said piston to lift or to depress it respectively, a piston rod extending from said piston, an engine and pump assembly supported by said piston rod and movable up and down, a follower carried by said assembly and engageable with the surface of the material in the container and having an opening for passage of said material, said pump comprising a cylinder, a plunger therein reciprocated by the engine, a bell connecting the cylinder with the opening in said follower, a lift cylinder between the pump cylinder and the bell, an extension from the plunger passing through said lift cylinder and into the bell, an elevator disc on said extension and movable throughout a substantial portion of the stroke freely in the bell and beyond the lift cylinder, said disc having a relatively loose fit and being movable in the lift cylinder throughout the remainder of the stroke, said pump cylinder having an outlet above the lift cylinder, and a check valve permitting only flow from the lift cylinder toward said outlet, the volumetric displacement of the disc in the lift cylinder being greater than the pump plunger during the time that said disc is movable in said lift cylinder, said follower being biased against the material by the weight of the pump and engine thereon.

22. Pumping apparatus comprising an assembly consisting of an engine, a pump, a follower adapted to rest upon material to be pumped, said follower having an opening, means connecting the pump with the follower and said opening comprising a bell, said pump having a pump cylinder, a plunger in the cylinder, a lift cylinder communicating with the pump cylinder, a check valve between said cylinders, and a lifting disc operable by the pump piston and movable into said lift cylinder, said pump having an outlet above said valve, and an accumulator with which said outlet is in communication and which is carried by the engine and pump assembly.
